CLAIM

The ornamental design for a telephone set, as shown
and described.

DESCRIPTION

FIG. 1 is a front, top and right side perspective view of
a telephone set showing my new design, with the
display panel of the stand in lowered position;

FIG. 2 is an inverted rear, left side and bottom perspec-
tive view thereof;

FIG. 3 is a perspective view thereof as in FIG. 1, but
with the display panel raised; and

FIG. 4 is an inverted perspective view thereof as in
FIG. 2, with the display panel in raised position.
